UNITED STATES PATENT OFFICE

LEOPOLD KOROPP, OF CHICAGO, ILLINOIS

FLORAL SPRAY

Application filed April 9, 1929. Serial No. 353,803.

My invention relates to floral sprays of the artificial type, as used for decorative purposes, and more particularly to the mounting of the sprays on supporting easels, and my 5 main object is to provide a novel means for mounting the sprays whereby to eliminate the use of the usual frame.

A further object of the invention is to employ a simple backing element as a foundation 10 for the support of the sprays.

A still further object of the invention is to employ simple means for the attachment of the spray to the foundation and the easel.

A final but nevertheless important object of 15 the invention is to design the invention with extreme simplicity.

With the above objects in view and any others that may suggest themselves in the specification and claims to follow, a better 20 understanding of the invention may be had by reference to the accompanying drawings, in which—

Figure 1 is an elevation of a spray mounted in accordance with my invention;

25 Figs. 2, 3, and 4, are, respectively, enlarged sections on the lines 2—2, 3—3, and 4—4 of Figure 1; and

Fig. 5 is a reduced elevation of the easel.

My improvement has particular application 30 to sprays which are curved in pairs to form a wreath-like assembly. In order for the sprays to retain their arcuate form as well as to hold to each other, it has been customary to mount them on a wire frame, and apply 35 clips or other fastening devices to the sprays for connection with the frame. This process involves the expense of the frame and also the labor of applying the fastening means at many points in order that the assembly may 40 be secure. Then, the frame body is applied and secured to the easel. In my improvement, I have eliminated the frame and substituted a simple method of securing the sprays to the easel whereby the form and 45 security of the assembly may be maintained.

Referring specifically to the drawings, 10 denote two artificial sprays, whose ribs are indicated at 11, the sprays being bowed toward each other to assume the circular form 50 of a wreath. The large ends of the ribs 11 are

more or less spaced while the opposite ends are preferably crossed, in order to blend the leaves.

The easel 12 commonly applied to sprays of the above kind is of inverted V-form and made of wire. The bend 12a of the easel is applied opposite the junction of the sprays at the top, and the front side of the easel at a lower point is fitted with a cardboard plate 13 whose position is opposite the lower ends of the sprays. The plate 13 is usually carried by the easel before applied to the sprays, and is fastened to the easel by band clips 14. The easel and plate are then applied as a unit to the back of the spray assembly.

At the top of the spray assembly, the crossed ribs 11 are secured to the bend 12a of the easel by a few clips 15; and clips 16 are employed to secure the lower portions of the ribs directly to the plate 13. The spray assembly is now firmly connected to the easel 12, and may be set vertically as shown in Figure 1, or fitted into any suitable environment in a corresponding position. Also, further ornamentation within the span of the sprays may be applied in any manner which suits the taste.

It will be seen that by means of the foundation formed by the easel 12 and the plate 13 a sufficient basis is provided for the laying 50 and connecting of the sprays whereby to assume and maintain the circular or wreath form without the need of a frame behind along which to train the sprays. The cost of the device is therefore materially reduced, 55 since both the easel 12 and the plate 13 involve but a nominal expense. Further, the sprays are firmly anchored at their strongest portions, which are opposite the plate 13, the latter serving as a broad and firm backing to retain the ribs of the sprays firmly and against loss of shape or change of direction. Finally, the application of the clips 15 and 16 serve to firmly secure the wreath assembly 60 both at the top and bottom to the easel assembly, whereby to form a sturdy and rigidly secured body. It will be obvious that the plate 13 may be of any suitable material, my reason for choosing cardboard being the low 65 cost and serviceable nature thereof.

I claim:

1. A floral wreath comprised of a pair of arcuate sprays with the ends thereof curved toward each other, fasteners securing together one set of spray end portions, a backing element for the other set of spray end portions, and fasteners securing the latter set to the backing element.

2. A floral wreath comprised of a pair of arcuate sprays with the ends thereof curved toward each other, each spray being founded on a tapered rib, fasteners securing together the thin spray-rib end portions, a backing element for the thick spray-rib end portions, and fasteners securing the latter end portions to the backing element.

3. A floral wreath comprised of a pair of arcuate sprays with the ends thereof curved toward each other, each spray being founded on a tapered rib, fasteners securing the thin spray-rib end portions in crossed relation, a backing card for the thick spray-rib end portions and fasteners securing the latter end portions in opposed relation to the backing card.

4. A floral wreath comprised of a pair of arcuate sprays with the ends thereof curved toward each other, fasteners securing one set of spray end portions together, a backing element for the other set of spray end portions, fasteners securing the latter to the backing element, and a spacing element between the first mentioned fasteners and the backing element.

5. A floral wreath comprised of a pair of arcuate sprays with the ends thereof curved toward each other, fasteners securing one set of spray end portions together, a backing element for the other set of spray end portions, fasteners securing the latter to the backing element, a rigid stay element secured to the first-named set of spray end portions and to the backing element.

6. A floral wreath comprised of a pair of arcuate sprays with the ends thereof curved toward each other, fasteners securing one set of spray end portions together, a backing element for the other set of spray end portions, fasteners securing the latter to the backing element, a V-shaped easel with its head secured by the first-named fasteners and its legs applied to the rear side of the backing element, and fasteners securing the legs to the latter.

7. A floral wreath comprised of a pair of arcuate sprays with the ends thereof curved toward each other, looped-staple fasteners securing one set of spray end portions together, a backing element for the other set of spray end portions, looped-staple fasteners securing the latter to the backing element, a V-shaped wire easel with its vertex secured by the first-named fasteners and its legs applied to the rear side of the backing element, and fasteners securing the legs to the latter.

8. A floral wreath comprised of a pair of arcuate sprays connected together to form substantially a circle, fasteners securing together one set of spray end portions, a backing element for the other set of spray end portions, and fasteners securing the latter set of end portions to the backing element.

In testimony whereof I affix my signature.

LEOPOLD KOROPP.
